(57) **CLAIM**

The ornamental design for a blood glucose meter, as shown and described.

DESCRIPTION

FIG. 1 is a top perspective view of a blood glucose meter;
FIG. 2 is a bottom perspective view thereof;
FIG. 3 is a top view thereof;
FIG. 4 is a bottom view thereof;
FIG. 5 is an end view thereof;
FIG. 6 is another end view thereof;
FIG. 7 is a right side view thereof; and,
FIG. 8 is a left side view thereof.
